(57) **CLAIM**

We claim the ornamental design for a partition, as shown and described.

DESCRIPTION

FIG. 1 is a top front/right perspective view of a first embodiment of a partition;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a front right perspective view thereof;

FIG. 9 is a top front/right perspective view of a second embodiment of a partition;

FIG. 10 is a front elevation view thereof;

FIG. 11 is a rear elevation view thereof;

FIG. 12 is a right side elevation view thereof;

FIG. 13 is a left side elevation view thereof;

FIG. 14 is a top plan view thereof;

FIG. 15 is a bottom plan view thereof;

FIG. 16 is a front right perspective view thereof;

FIG. 17 is a top front/right perspective view of a third embodiment of a partition;

FIG. 18 is a front elevation view thereof;

FIG. 19 is a rear elevation view thereof;

FIG. 20 is a right side elevation view thereof;

FIG. 21 is a left side elevation view thereof;

FIG. 22 is a top plan view thereof;

FIG. 23 is a bottom plan view thereof; and,

FIG. 24 is a front right perspective view thereof.

The uniform broken lines in FIGS. 1-8 are for the purpose of illustrating environment that form no part of the claimed design. Non-uniform broken lines in FIGS. 1-24 are for the purpose of illustrating surfaces and contours but do not define boundaries or other hard edges of the claimed design.
